(57) **CLAIM**

The ornamental design for a triangular penlight, as shown and described.

DESCRIPTION

FIG. 1 is a perspective view of the triangular penlight showing a front, bottom, and left sides of our new design; FIG. 2 is a front view of the triangular penlight of FIG. 1; FIG. 3 is a rear view of the triangular penlight of FIG. 1; FIG. 4 is a right side view of the triangular penlight of FIG. 1, the left side view is a mirror image of the right side view and is therefore not shown;

FIG. 5 is a top view of the triangular penlight of FIG. 1; and, FIG. 6 is a bottom view of the triangular penlight of FIG. 1.
